UNITED STATES PATENT OFFICE.

FRANK VAUGHAN, OF ELIZABETH CITY, NORTH CAROLINA.

BOAT HOISTING, DETACHING, AND LOWERING.

SPECIFICATION forming part of Letters Patent No. 282,937, dated August 7, 1883.

Application filed January 18, 1883. (No. model.)

To all whom it may concern:

Be it known that I, FRANK VAUGHAN, a citizen of the United States of America, residing at Elizabeth City, in the county of Pasquotank and State of North Carolina, have invented 5 certain new and useful Improvements in Boat Lowering, Hoisting, and Detaching, of which the following is a specification, reference being had therein to the accompanying drawings.

10 My invention relates to devices for hoisting and lowering boats; and it consists in the construction and arrangement of its several parts, as will be hereinafter fully set forth.

In the drawings, Figure 1 is a cross-section of a portion of a ship, showing my boat lowering and detaching device attached thereto. Fig. 2 is a view as above, showing the boat hoisted overboard. Fig. 3 is a side elevation of the hoisting and lowering device, showing 20 boat in position therein. Fig. 4 is a top plan view of the cradle-bed; Fig. 5 a longitudinal section of the central longitudinal beam. Fig. 6 shows details of the cradle and socket, and Fig. 7 are views of the stay or brace rods.

25 A represents the cradle-bed. It is formed of a central beam, A', having contracted end prolongations, a, and parallel slots A², secured to bars A³, secured at right angles across the ends and middle of the central beam, as shown, 30 the outer slots, A³, having contracted end prolongations, a', equal in length to a, and have depending from end the rests or legs a², as shown. The central beam, A', is provided with vertically-socketed projections a³, in which are received and keyed the cradles B, as shown.

35 a⁴ represents the brace or stay rods. They are formed with centrally-located openings, which fit over the projection a³, and are attached to the central beam upon each side 40 thereof, as shown. It will be seen that these rods cross each other between the projections, the rods from the end projections being secured to the ends of the beam, as shown.

45 Bare the cradles. They are made Y or prong shaped, the prong portion b being shaped to fit as nearly as possible to the sides of the boat, so that a support thereto may be afforded along their entire length. The standard b' of the

cradle enters the socket a³, its lower end projecting through and keyed by the pin b², as 50 shown. The cradles are set at right angles to the frame, and each one is of different shape from the others, in order to embrace the boat closely at all points in its length.

Secured to the ends of the slats A³, and to 55 the central beam, are the hoisting-chains C. They meet at some distance above the cradle-bed and continue in a single chain, C', over the hinged derrick D, inboard, whereby they may be attached to a windlass or other suitable 60 hoisting device. I control the motions of this derrick by journaling it in a cap, E, the sides of which project upwardly in the form of lips c, and prevent the derrick from swinging too far in either direction, as set forth.

In the operation of the device in Fig. 1 the 65 boat is shown resting in its cradle upon the ship's deck. When it is desired to lower the boat, it is raised by means of the chains C until the cradle clears the deck. The derrick is then 70 pushed outboard until the cradle clears the side of the ship. The cradle is then lowered until it sinks far enough beneath the water to 75 permit the boat to float off freely.

What I claim is—

1. A device for hoisting and lowering boats, 80 consisting of the combination, with the hoisting-chains, of a bed or platform having a central beam, A', provided with sockets a³, and a series of Y-shaped cradles to receive the boat, substantially as set forth.

2. In a device for hoisting and lowering boats, 85 a bed or platform consisting of a central beam, A', a series of parallel slats, A², and cross-bars A³, the diagonally-arranged braces a⁴, and feet a², said central beam being provided with socketed projections a³ to receive the shanks of a series of cradles B, substantially as set forth.

In testimony whereof I affix my signature, in presence of two witnesses, this 20th day of December, 1882.

FRANK VAUGHAN.

Witnesses:

P. PRINTZ,
W. J. OSGOOD.
